UNITED STATES PATENT OFFICE.

SAMUEL B. DURBIN, OF TULSA, AND JOSIAH V. BOLTON, OF JENKS, OKLAHOMA.

CIRCLE BRACE.

Application filed March 10, 1923. Serial No. 624,186.

To all whom it may concern:

Be it known that we, SAMUEL B. DURBIN and JOSIAH V. BOLTON, citizens of the United States, residing at Tulsa and Jenks, respectively, in the county of Tulsa and State of Oklahoma, have invented certain new and useful Improvements in Circle Braces, of which the following is a specification, reference being had to the accompanying drawings.

This invention relates to certain improvements in circle braces and it is an object of the invention to provide a device of this general character with novel and improved means whereby the same will not break or slip when in use and which may be readily adjusted as the occasions of practice may demand.

It is also an object of the invention to provide a novel and improved device of this general character wherein the jaw is secured to the body of the brace in a manner whereby the jaw will square against the drilling tools irrespective of the angle in which the body of the brace may be arranged.

The invention consists in the details of construction and in the combination and arrangement of the several parts of our improved circle brace whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawings, wherein:

Figure 1 is a view in side elevation of a circle brace constructed in accordance with an embodiment of our invention and in applied position, the coacting drilling tool and rack of the oil well jack being indicated by broken lines;

Figure 2 is a view in plan of the brace as herein disclosed;

Figure 3 is a view partly in elevation and partly in longitudinal section of the device as herein disclosed;

Figure 4 is a view in plan of the base adapted to be employed with the brace to turn said brace into a jack;

Figure 5 is a cross sectional view of the base illustrated in Figure 4.

As disclosed in the accompanying drawings, 1 denotes a jaw made of high grade steel and tempered to prevent the wickers 2 formed on the working face of said jaw from flattening. The rear of the jaw 1 is provided with an outstanding flange 3 which snugly fits within a groove 4 provided in the adjacent face of the head 5. Extending through the head 5 and the flange 3 of the jaw 1 is a pin 6 whereby said jaw 1 and head 5 are effectively maintained in assembled relation.

The inner or opposite face of the head 5 is provided with a socket 7 in the base portion of which snugly fits the ball 8 arranged at an extremity of an elongated threaded member or shank 9. Disposed through the ball 8 of the adjacent portion of the head 5 is a pin 10 for maintaining said head 5 and member or shank 9 in assembled relation. The connection between the head 5 and the member or shank 9 permits the jaw 1 to sit square against the drilling tools, as illustrated in Figure 1.

11 denotes an elongated tubular body or member having its opposite ends open and inserted within the opposite end portions of said body or member 11 are the sleeves 12 preferably pressed in applied position. The member or shank 9 is threaded through one of the sleeves 12 while threaded through the second sleeve 12 is an elongated member or shank 14. It is to be noted that the members 9 or shanks 9 and 14 are reversely threaded so that upon rotation of the member 11 the brace will be lengthened or shortened as the necessities of practice may prefer.

The outer extremity of the member or shank 14 is flattened as at 15 and is adapted to abut, when the brace is in applied position, against the rack 16 of an oil well jack such as the "Barrett." Our improved brace when applied effectively accomplishes the purposes desired and by the use of our improved brace time and labor is saved owing to the fact that said brace is light, strong, safe and quick adjustable.

It is also possible to employ our brace as a jack and in so doing we employ a base 17 having in its central portion a slot or recess 18 in which is fitted the flattened or tapered portion 15 of the member or shank 14. When used as a jack our improved device has been found to be of special importance in jacking up sand reels, bull wheels, shafts and bearings and also for moving engines, 10 engine foundations, etc. We also find our improved device to be of particular advantage for moving wire lines or any other thing of ordinary heft.

From the foregoing description it is 15 thought to be obvious that a circle brace constructed in accordance with our invention is particularly well adapted for use by reason of the convenience and facility with which it may be assembled and operated, and 20 it will also be obvious that our invention is susceptible of some change and modification without departing from the principles and spirit thereof and for this reason we do not wish to be understood as limiting ourselves

to the precise arrangement and formation of 25 the several parts herein shown in carrying out our invention in practice except as hereinafter claimed.

We claim:—

A device of the class described comprising 30 a tubular body, threaded shanks engaged with the opposite end portions of the body, said shanks being reversely directed, a head provided with a socket, the outer extremity of one of the shanks being provided with a 35 ball snugly fitting within the base portion of the socket of the head, a pin connecting said head and ball, a face of the head remote from the socket being provided with a groove, a jaw having a flange fitting within 40 said groove, and means coacting with said head and flange for holding the jaw in applied position.

In testimony whereof we hereunto affix our signatures.

SAMUEL B. DURBIN.
JOSIAH V. BOLTON.
